UNITED STATES PATENT OFFICE.

CARLEY GOULD WELD, OF NORTH CHATHAM, MASSACHUSETTS.

POWER FLUID-ACTUATED IMPULSE-PUMP.

1,114,951.

Specification of Letters Patent.

Patented Oct. 27, 1914.

Application filed October 23, 1912. Serial No. 727,280.

To all whom it may concern:

Be it known that I, CARLEY GOULD WELD, a citizen of the United States, residing at North Chatham, in the county of Barnstable and Commonwealth of Massachusetts, have invented certain new and useful Improvements in Power Fluid-Actuated Impulse-Pumps, of which the following, taken in connection with the accompanying sheet of drawings, forms a full, clear, and concise description.

My invention relates particularly to that class of pump which is designed for attachment to an internal combustion engine by connection with the spark-plug opening of the engine cylinder, the pump being operated by the engine compression. Pumps of this character have found special service in inflating pneumatic tires of automobiles, and while my invention has been primarily devised for this particular purpose, I do not wish to be understood as limiting myself in this respect, as the pump may be used as a compressor for charging tanks with pressure or put to other specific uses to equal advantage.

My invention comprehends a pump of this character having triple cylinders of equal diameter arranged in tandem, the cylinders having reciprocated connected pistons therein, means being provided for the passage of the operating fluid through the cylinders and for the further compression of it by the pistons therein.

Another feature of my invention is to provide a novel form of air-inlet or pressure-valve.

Referring to the accompanying sheet of drawings, Figure 1 illustrates a vertical section of a pump made in accordance with my invention. Fig. 2 is a fragmentary detail of the lower portion of a pump modified to accommodate the inlet or breather valve which I have designed for the purpose of admitting air to the engine cylinder.

In detail, the numerals 1, 2, and 3 indicate superimposed cylinders connected in tandem by means of collars 4 and 5. Separating these cylinders are partitions 6 and 7, forming three compression chambers in which pistons 8, 9, and 10 reciprocate, for the compression and stepping-up of the operating fluid which emanates from the engine cylinder upon the compression stroke of the piston therein. The ends or extremities of the pump are provided with

caps 11, 12, cap 11 being provided at its lower extremity with a threaded extension 13, adapted to screw into the screw-threaded spark-plug opening of the engine to 60 which it is attached. The upper cap 12 is provided with a ball-check-valve 14, normally held to its seat by a spring 15. This ball-check-valve is permitted a small amount of movement under the action of 65 the air pressure being delivered, a pin 16, projecting from the cap 17, permitting and limiting this movement. Extending laterally from the upper portion of the cap 12 is an outlet 18, having a screw-threaded end 70 or nozzle to which the flexible tube which conveys the air to the tire is connected. Reciprocally mounted within the cylinders are the pistons, which are connected one to another in tandem by means of two hollow 75 piston-rods 19 and 20, which in turn are connected together by means of a screw-threaded coupling 21. The top of this coupling is ground out to provide a seat member for the ball-check 22, which is normally 80 held to its seat by the spring pressure exerted by the spring 23, the movement of the ball-check 22 being limited by a depending pin 24, which also serves to retain the spring in alined position. The piston 85 25 is connected to the lower end of a hollow piston-rod by means of a screw-threaded connection 25 and a set-screw 26. A collar is provided with a laterally-extending flange 27, having an extension 28, which 90 fits within the bore of the lower cap 11, for the purpose of cushioning the piston at the end of its down stroke by the trapping of the fluid between the flange 27 and the cap 11. Mounted upon the flange 27 is an inverted cup-shaped leather washer 29. Between this washer and the lower portion of the hollow piston-rod 19 is a cup-shaped metal guide member 30. The piston 9, which is connected to and carried by the 95 screw-threaded coupling 21, consists of a cup-shaped leather washer 31, clamped between a cup-shaped metal member 32, and an inverted cup-shaped metal guide member 33, these being fastened together by suitable 100 screws 34. The metal guides 30, 33, and 36 do not fit the cylinders closely, a slight clearance being allowed to provide for the passage of atmospheric air and compressed 105 air during the operation of my pump.

The construction of the piston 10 is somewhat similar to the construction of the pis-

ton 8, a leather washer 35 being clamped between a cup-shaped metal guide 36, and the disk 37, having an extension 38, in threaded connection with the upper section 20 of the hollow piston-rod. The partitions 6 and 7 are provided with packing members 39, which bear upon the hollow piston and serve to make air-tight connections. These packing members are mounted upon the partitions between the same and metal washers 40, by means of suitable screws 41. The hollow piston is provided with ports or openings 42, forming passages between the hollow piston-rod and the lower side of the piston 9. Similar ports 43, are provided leading from the upper portion of the hollow piston rod to the under-side of the piston 10. The cylinders 1 and 2 above the pistons 8 and 9 are provided with a plurality 20 of ports 44, opening to the atmosphere, for the admission of air to be compressed and also to act as part of the cushioning means to cushion the upward blow of the piston.

Referring in detail to Fig. 2, the lower 25 cap 11 is provided with a breather valve which consists of a flat valve member 47, positioned between the screw-threaded coupling 48 and the cap 11 and normally held seated against the top of the coupling 48 by 30 means of a spring 49. The coupling 48 has a screw-threaded connection at 50 with the cap 11 and is provided with a plurality of circumferentially-arranged ports or openings 51, for the admission of air to the engine 35 cylinder upon the suction stroke of the piston therein.

The operation of my pump may be conveniently described as follows: It will be understood that the screw-threaded end 13 40 of the pump is attached to the screw-threaded spark plug opening of one cylinder of a multi-engine cylinder, the spark plug being removed, rendering the pump operative by the compression of the engine only. Assuming 45 that the pistons are in the position shown in the drawing, the upstroke of the engine piston compresses the fluid in the engine cylinder forcing such compressed fluid through the passage of the hollow piston 19 50 and out through the ports 42, while a portion passes around the lower extension 28 and underneath the lower piston. Compressed fluid also lifts the valve 22 and passes out through ports 43 to the underside 55 of the piston 10. This pressure acting between pistons 10, 9 and 8 and the immovable partitions 7 and 6 and the cap 11 causes the pistons to move upwardly, the upper piston 10 compressing the contents of the cylinder 3 and forcing it to the tire or other receptacle where fluid pressure is desired.

Before the pistons reach the extreme limit of their upward stroke, the cup-shaped metal guide members 30 and 33 coöperate 60 with the ports 44 in both cylinders 1 and 2

to trap air between the guide members and partitions 6 and 7. This results in cushioning the upward stroke of the pistons and prevents damage or destruction of the parts. When the engine piston is negotiating its 70 downward stroke, the compressed air, which has previously been trapped between the piston 10 and the partition 7, is caused to bleed or pass around the metal guide member 36 into the upper cylinder or compression 75 chamber above the piston 10, where it is further compressed on the succeeding upward stroke of said piston. The cup leather washer 37, it will be understood, assumes a state of collapse on the downward stroke, 80 permitting the air to pass it, in the well-known manner. It will likewise be understood that the compressed fluid is compelled to pass into the upper compression chamber, 85 as the valve 22 is held to its seat preventing said compressed fluid from reëntering the engine cylinder by reason of the suction tendency of the piston therein upon this downward stroke.

Simultaneously with the downward stroke 90 of the piston, which is caused by the suction power of the engine piston, atmospheric air is sucked through the ports 44 and bleeds pass the metal guides 30 and 33 and the leather washers 29 and 31 (which assume a 95 state of collapse on this down stroke). The air entering from cylinder 2, passes through ports 42 and down through the hollow piston 19 commingling with the air entering the ports 44 of cylinder 1. This air then enters through the spark plug opening of the engine into the engine cylinder, where it is compressed on the succeeding upstroke of the engine piston, thus causing the pump to 100 further operate in the manner just described. When the projecting end 28 of the member 27 enters the bore of the spark plug connecting end 13 of the pump, air is trapped 105 between the piston 8 and cap 11, forming a cushion and absorbing the power of the blow of the downward movement of the pump pistons. It is thought that this description will be sufficient for a full understanding of the operation of the invention. 110 A repetition of the cycles or movements of the engine and pump pistons, as just explained, causes the production of the desired volume of compressed fluid. 115

Referring to Fig. 2, I would say that with 120 this construction, I am enabled to make the cup-shaped guide members 30 and 33 so that they will have a close sliding fit with the walls of the cylinders 1 and 2, not relying upon the admission of the air through ports 125 44 of the pump cylinders to increase the engine compression and the pressure of the operating fluid. In this instance, the ports 44 will also act as a cushion expedient upon the upward stroke of the pump pistons. It will 130 be understood where this modified construc-

tion is used, atmospheric air will be sucked in through the breather ports 31, unseating the disk valve 47 against the tension of the light spring 49, this air being sucked into 5 the engine cylinder.

By reason of the construction of my pump, as heretofore explained, I am enabled to reduce the diameter of a compound pressure producing pump of this class, still obtaining 10 the same amount of pressure as would be obtained if differential cylinders were used. That is to say, instead of having a large power cylinder and a small compressing cylinder, I employ two power cylinders of equal 15 diameter, the joint capacity of which is equal to the capacity of a single power cylinder of a differential pump of equal efficiency. In addition to this, by reason of the particular 20 construction of my pump, I am enabled to manufacture it at small cost, utilizing metal stampings and tubing in the place of cast metal parts.

Having thus described my invention, what I claim as new herein and desire to secure by 25 Letters Patent is:

1. An impulse pump adapted to be operated by the compression of an internal combustion engine, comprising a plurality of cylinders of equal diameter, one of which is 30 adapted to be brought into screw-threaded engagement with one cylinder of said engine, pistons reciprocally mounted within said cylinders and means for admitting to the underside of each piston, fluid pressure that has 35 previously been compressed in the cylinder of said engine to which said pump is attached.

2. An impulse pump adapted to be operated by fluid pressure comprising a plurality 40 of cylinders of equal diameter arranged in tandem, connected pistons therein, means for admitting to the underside of each piston fluid under pressure to operate them on their working stroke, and means for permitting 45 the air in one of said cylinders to pass the piston on the suction stroke to enable the piston to compress it upon its succeeding working stroke.

3. An impulse pump adapted to coöperate 50 with the cylinder of an internal combustion engine, comprising a plurality of cylinders of equal diameter arranged in tandem, a reciprocating piston in each cylinder, a hollow connecting piston-rod connecting the respective pistons, said rod being provided with ducts or passages communicating with the underside of two of said pistons, and a check-valve controlling the passage through the hollow piston connecting rod, substantially 55 as described.

4. A pump of the character described, comprising a plurality of power cylinders adapted to receive compressed fluid from a source

of supply, actuating pistons in said power cylinders operated by said compressed fluid, 65 a pressure cylinder, means of communication between said power cylinders, a valve-controlled means of communication between said power cylinders and said compression cylinder, 70 said piston being connected and operated simultaneously with the pistons in the power cylinders, substantially as described.

5. A spark plug pump of the character described, the combination of a plurality of 75 power and compressing cylinders of the same relative diameter, simultaneously operated pistons in said cylinders, means for affording communication between said cylinders for the operating fluid to the underside of said 80 pistons to cause them to move on their working stroke so that the piston in the compression cylinder will perform its compression operation, and means for trapping the compressed fluid below the piston in the compression cylinder so that upon the down stroke of said piston, said fluid will be caused 85 to flow into the compression chamber above said piston and be compressed by its succeeding stroke. 90

6. A spark plug pump of the character described, comprising a plurality of connected cylinders of equal diameter, a plurality of connected pistons reciprocally mounted within said cylinders and adapted 95 to be operated by the fluid compression of one cylinder of an internal combustion engine, means for causing said compressed fluid emanating from said engine to actuate said pistons and means for increasing the 100 pressure of said engine compression fluid to a higher pressure by one of the pistons of the pump.

7. A spark plug pump of the character described, comprising three cylinders of equal 105 diameter in tandem, a piston in each cylinder, a piston rod provided with a passage communicating with the respective cylinders connecting the pistons in the respective cylinders, a valve controlling the passage 110 through the piston rod, and means for admitting the fluid compression of one cylinder of an internal combustion engine to the underside of each piston, and means for causing the passage of said engine compression 115 fluid to the compression space above one of the pistons to be compressed thereby to a higher pressure and a valve controlled outlet for said compressed fluid.

In witness whereof I have hereunto set my 120 hand in the presence of two subscribing witnesses.

CARLEY GOULD WELD.
